UNITED STATES PATENT OFFICE

172,199

HANDLE FOR ELECTRICAL SOLDERING IRONS OR THE LIKE

Alexander Schoenwald, Grove City, Pa., assignor
to P. Wall Mfg. Company, Grove City, Pa., a
corporation of Pennsylvania

Application May 11, 1953, Serial No. 24,931

Term of patent 14 years

(Cl. D26—1)

To all whom it may concern:

Be it known that I, Alexander Schoenwald, a citizen of the United States of America, residing at Grove City, Pennsylvania, have invented a new, original, and ornamental Design for a Handle for Electrical Soldering Irons or the like, of which the following is a specification, reference being had to the accompanying drawing forming a part hereof.

Figure 1 is a side view of a handle for electrical soldering irons or the like embodying my design;

Fig. 2 is a plan view thereof;

Fig. 3 is a front end view of the structure of Fig. 1, and

Fig. 4 is a rear end view of the structure of Fig. 1.

I claim:

The ornamental design for a handle for electrical soldering irons or the like, as shown.
